UNITED STATES PATENT OFFICE.

CHARLES E. SARGENT, OF INDIANAPOLIS, INDIANA, ASSIGNOR TO MIDWEST ENGINE COMPANY, OF INDIANAPOLIS, INDIANA, A CORPORATION OF INDIANA.

DESIGN FOR A TRACTOR.

57,381.

Specification for Design.

Patented Mar. 15, 1921.

Application filed March 24, 1920. Serial No. 368,425. Term of patent 14 years.

To all whom it may concern:

Be it known that I, CHARLES E. SARGENT, a citizen of the United States, residing at Indianapolis, in the county of Marion and State of Indiana, have invented a new, original, and ornamental Design for Tractors, of which the following is a specification, reference being had to the accompanying drawing, forming part hereof.

The single figure of the drawing is a perspective view taken from the side, of a tractor, showing my new design.

I claim as my invention:

The ornamental design for a tractor, as shown.

In witness whereof I have hereunto set my hand at Indianapolis, Indiana.

CHARLES E. SARGENT.
